HIRAM BASSETT NICKERSON, OF BOSTON, MASSACHUSETTS.

Letters Patent No. 70,458, dated November 5, 1867.

IMPROVED MACHINE FOR CUTTING TEETH OF FILE-BLANKS.

The Schedule referred to in these Letters Patent and making part of the same.

TO ALL PERSONS TO WHOM THESE PRESENTS MAY COME:

Be it known that I, HIRAM BASSETT NICKERSON, of Boston, of the county of Suffolk, and State of Massachusetts, have invented a new and useful Machine for Cutting or Making the Teeth of File-Blanks; and I do hereby declare the nature of the said invention, and the manner in which it is to be performed or is constructed and operates, to be fully described in the following specification, reference being had to the accompanying drawings, making part thereof, and of which—

Figure 1 is a top view,

Figures 2 and 3 side elevations,

Figure 4 a rear elevation, and

Figure 5 a longitudinal and vertical section of it.

In my said machine I have two cutters, and mechanisms for raising and depressing them. I also have a file-blank supporting-carriage, and mechanism for imparting to it an intermittent motion in one direction, for the purpose of enabling each of the cutters to form the indentures in the file-blank at their proper distances asunder. I also have a mechanism for arresting the operation of one cutter and its depressing mechanism, and maintaining such out of action, while the other cutter and its operative mechanism may be at work to produce the balance of the cuts to be made by such cutter in the file-blank.

Furthermore, I have in such machine mechanism for gradually increasing the force of the blow of either hammer or its cutter-carrier, while the cutter thereof may be passing from the thinnest to the thickest, or from the narrower to the wider part or parts of the file-blank.

I also have a peculiar mechanism for effecting the feeding movements of the file-blank carriage. The two cutters are arranged so that the cuts made by one in the blank shall be crossed by those made by the other, the same being to produce what are termed cross-cut or bastard files.

In the drawings, A and B are the two cutters, the front one of which, viz., A, stands oblique or at an angle with the other, and both are arranged over a carriage, C, supported on the base-plate D of the frame, so as to be capable of being moved rectilinearly thereon in the direction of the length of the said carriage. Each cutter is fixed in one of two blocks or heads *a a*, each of such heads being jointed to one of two slides or carriers *b b* in such manner as to be capable of rocking or turning laterally on a centre or centre-pin, and independently of a force-transmitter, *c*, affixed to the carrier, and extending down to the cutter-head in manner as represented in the drawings, and particularly in Figures 6 and 7, the first of such figures being a section of the cutter-head and force-transmitter, taken in a plane parallel with the front face of the cutter-carrier.

Fig. 7 is a vertical section taken through the inner cutter, its hammer and the poppet or standard for supporting the said carrier.

The two cutter-carriers *b b* are sustained by and so as to be capable of being moved upward and downward in two standards *E E'*, erected on the base-plate, and arranged thereon in manner as represented in the drawings, the file-blank carriage *C* being arranged between such standards. In rear of the two standards *E E'*, and supported in boxes *d d* at the upper parts of two posts *e e*, erected on the base-plate, is a driving-shaft, *F*, which carries an eccentric, *f*, and four cams, *g h i k*, the shapes of such cams and eccentric being exhibited in the drawings. Each of the two inner cams *h i* is for the purpose of operating one of two levers *l l*, which have their fulcra projecting from the two standards *E E'*, or from the sides of two buffers *m m*, and are connected by links *n n* to the carriers *b b*. Thus the said cams *h i* and the levers are for effecting the elevation of each of the said carriers and its cutter at the proper times with respect to the file-blank shown at *o* as placed on the carriage *C*, and held down thereupon by a presser, *G*. The said presser is hinged to one of the standards *E E'*, and pressed downward by a lever-spring, *P*, whose rear arm is placed in one of a series of notches of a vertical rack, *q*, the whole being arranged as represented in the drawings.

The two outer cams *g k* are for actuating or raising two hammers *H H*, whose fulcra *r r* are upheld by the two standards *E E'*. These hammers are to strike on the upper ends of the two force-transmitters *c c*. There is a spring, *s*, applied to each of the hammers and its standard, such spring being for effecting a depression of the hammer when relieved from its elevating-cam.

Underneath the base-plate D, and duly supported in bearings t t , is a screw-shaft, I, which is confined by a nut, K, extending from the file-blank carriage C, such nut being formed in two parts or jaws, as shown at u u in Figure 8, and hinged together, and provided with a catch, v, for holding them in connection with the screw-shaft. The said nut extends down through a slot, w, made in the base-plate.

A ratchet, x, is fixed on the rear end of the screw-shaft, and engages with two pawls y z, arranged with respect to it in manner as shown in fig. 4. These pawls are supported on pins projecting from two rocker-levers or plates a' b', which turn on the screw-shaft, and are connected to two other levers, e' f', by two connection-rods e' e'. From one of the levers e' f' a stud, g², extends into a slot, h', made in the other, the same being as shown in fig. 4. The two levers have their fulcra i' i' projecting from the base-plate, and there is jointed to the shorter arm of the longer lever a rod, k², which extends from a hoop or annulus, l', encompassing the eccentric f. During each revolution of the said eccentric the two pawls will be caused to act successively upon the ratchet so as to partially revolve it, one pawl running over it while the other may be running it.

A movement of the carriage C will thus be produced preparatory to each blow of each hammer, tending to depress the cutter of such hammer. Against one side of the carriage C a pattern-guide, m', is fixed. A stud, n', extended from a forked lever, o', bears against the lower edge of the guide m', such edge corresponding in shape with the curve or taper of the upper surface of the file-blank. The fulcrum of the forked lever is supported by the adjacent standard E', and the fork of the lever receives a projection, p', from a sliding wedge or cam, q', on whose inclined upper surface rests the lower end of the shank r¹ of a buffer, m. This buffer is arranged directly underneath the shank of the hammer H, the shank of the buffer extending vertically through the standard and resting upon the wedge q'. As the file-blank carriage C may advance, the buffer will be gradually lowered so as to increase the force of the blow of the hammer, while the cutter may be forming the indentations of the tapering portion of the file, and be passing from the thinnest to the thickest part of such portion.

This last-described mechanism for increasing the force of the blow of the hammer is to be applied to each hammer, although in the drawings it is exhibited as applied to one, and but partially to the other. As the width of the file at its end is generally less than the width at or near the middle, and as the width gradually increases from each end to the middle of the file, it will be seen that were the blows on the cutter to be alike, the depth of the cuts at the end would be greater than at the middle of the file; therefore, by increasing the force of the blow of the hammer, as the cutter may be passing from the narrowest to the widest part of the file, we insure evenness of depth of cut.

The next part of the machine to be described is the mechanism for arresting the operation of one cutter and its depressing mechanism or hammer, and maintaining such out of action, while the other cutter and its operative mechanism may be at work to produce the balance of the cuts to be made by such second cutter. After one cutter may have effected its series of cuts, the other has to be kept in operation to complete the series of cross-cuts to be made by it.

Against the side of the carriage is a cam-bar, r², which operates with a bent lever, s', connected with another such lever, t', by a rod, u'. The lever t' is connected with the longer arm of a third lever, v', by a connecting-rod, w', to which and the adjacent standard a spring, x', is fastened, the purpose of the spring being to raise the rod so as to turn the latch-lever v' on its fulcrum, in order to cause the smaller arm of the said lever to pass underneath the hammer-shank, and hold the hammer up out of action upon its force-transmitter. A spring, y', is arranged on the base-plate, and underneath the longer arm of the bent lever s', the whole being as represented in the drawings. When the carriage may have attained its proper position for the stoppage of action of the cutter, the tail of this lever s' will pass off the cam-bar so as to allow the spring x' to raise the rod w', so as to lower the latch-lever on its fulcrum, and in a manner to cause the smaller arm of such latch-lever to pass underneath the hammer-shank, and hold the hammer out of action upon its force-transmitter. After full retraction of the carriage C, so as to draw the cam-bar out of action upon the lever s', the tail of such lever will be caused to fly upward, so as to allow the cam-bar, when the carriage C is next advanced, to pass underneath and raise the tail of the lever s', and thereby cause the latch-lever v' to be moved from underneath the hammer-shank, in order that the hammer may again fall upon the force-transmitter, and again go into operation.

Although I have shown the last-described mechanism as applied to but one of the standards and its hammer, it is to be borne in mind that a similar mechanism for the same purpose is to be applied to the other standard and its hammer.

Having thus described my said machine, what I claim therein as of my invention is as follows:

I claim the combination as well as the arrangement of the two cutters A and B, provided with mechanisms for raising and depressing them, as specified, with the file-supporting carriage C, having mechanism for imparting to it an intermittent motion in one direction, substantially as and for the purpose hereinbefore explained.

And I also claim the combination of such, and mechanism substantially as described, or its equivalent, for arresting the operation of a cutter and its depressing mechanism or hammer, and maintaining such out of action preparatory to and while the other cutter and its operative mechanism may be at work, to produce the balance of the cuts to be made by such cutter last mentioned, the said additional mechanism being the cam-bar r², the levers s' t', the rod u', latch-lever v', connecting-rod w', and springs x' and y'.

I also claim the combination of parts constituting such additional mechanism.

And in combination with the file-supporting carriage C, its operative mechanism, and the two cutters A B, provided with mechanism for effecting their elevations and depressions, I claim mechanism substantially as described, or its equivalent, for gradually increasing the force of the blow of a hammer while the cutter thereof may be passing from the narrower to the wider parts of the file-blanks, as explained, such last-mentioned mechanism being the pattern-guide m', stud n', forked lever o', projection p', wedge q', and buffer m, arranged as explained.

I also claim the combination of the guide m' , stud n' , forked lever o' , projection p' , wedge q' , and buffer m , the whole being for the purpose as explained.

And in combination with the file-supporting carriage C, its operative mechanisms, and the two cutters A B, and their mechanisms for effecting their proper elevations and depressions, I claim the spring-presser or its equivalent.

I also claim the combination of the self-adjusting cutter-head a with the carrier-slide b and the force-transmitter c , applied to the carrier as set forth.

I also claim the combination or mechanism for operating the feeding-screw, such consisting of the ratchet x , the pawls $y z$, rocker-levers $a' b'$, levers $e' f'$, and rods $c' c'$, rod k^2 , hoop l' , and eccentric f , arranged, constructed, and applied together so as to operate as specified.

H. B. NICKERSON.
